BED SPRING

Stephen J. Blaha, De Kalb, Ill., assignor to The
Englander Company, Inc., Chicago, Ill., a cor-
poration of Delaware

Application August 9, 1943, Serial No. 497,911

9 Claims. (Cl. 5—267)

1

The invention relates to bed springs and the general aim of the invention is to provide a new and improved bed spring in which the resilient action of the structure is enhanced and the use of materials made critical by the present national emergency is minimized.

An object of the invention is to provide in a bed spring construction embodying a plurality of spaced vertically arranged coil springs and a plurality of laterally or horizontally arranged smaller helical springs, new and improved means extending between the coil springs affording adequate anchorage for the helical springs, said means being quite flexible and resilient in opposition to the compressive forces exerted on the structure in use.

Another object is to provide new and improved means for securing the lower ends of the coil springs to wooden cross rails on the frame.

Other objects and advantages will become apparent from the following description and from the accompanying drawing, in which:

Figure 1 shows in plan view a corner section of a bed spring embodying the features of the invention.

Fig. 2 shows in cross section the details of assembly of one of the coil springs, the section being taken substantially along the line 2—2 of Fig. 1.

Fig. 3 is a view corresponding substantially to Fig. 1 but showing a different arrangement of the various elements of the structure.

Fig. 4 is a fragmentary view of a bed spring illustrating a modified form of means to which the coil springs are connected.

Fig. 5 is a fragmentary view on an enlarged scale more clearly illustrating the form of the anchor means for the small springs shown in Figs. 1 and 2.

Fig. 6 shows on an enlarged scale a modified form of the anchoring means.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

As shown in the drawings, the present invention is illustrated as being embodied in a bed spring structure which includes a bottom frame 10 of the usual rectangular form fashioned of

angle iron. A plurality of large coil springs 11 are supported on the frame with the axes thereof extending vertically. These springs are usually arranged in longitudinally and transversely aligned rows, the outer rows being supported directly by the bottom frame 10. The intermediate rows are supported on transversely extended cross rails 12 herein shown as extending transversely of the frame.

Because of the shortage of critical materials and the limitations imposed on the use thereof, the cross rails in the present instance are formed of wood. The coil springs may be easily and effectively anchored in the wooden cross rails by providing a pair of bores 13 for each spring to be secured to the cross rail, these bores being spaced longitudinally of the cross rail and extending horizontally therethrough. The bores are dimensioned and arranged to permit the lower turn of a coil spring to be threaded first through one bore and then through the other. The relationship is such that this lower turn is slightly distorted whereby its resiliency secures the spring firmly to the cross rail.

The upper surfaces of the coil springs are located on substantially the same horizontal plane, which plane is the upper surface of the bed spring structure. A border wire 14 extends continuously about the upper turns of the outer rows of the coil springs and is suitably secured thereto as by clips 15.

Each square formed by four joining coil springs is diagonally traversed by spring means connected to the upper turns of these coil springs and lying substantially on the horizontal plane thereof to exert their forces crosswise of the axes of the coil springs. As herein shown, this spring means for each diagonal arrangement is composed of small helical springs 16 connected one to the upper turn of each coil spring. Heretofore these helical springs were connected at their adjoining ends to a common sheet metal strip extending between adjoining rows of the coil springs. These strips were usually formed of thin 45 gauge sheet metal and, although somewhat resilient, added little to the weight supporting resiliency of the spring system as a whole.

Instead of such strips, I have provided new and improved anchoring means for the adjoining ends of the helical springs which uses much less metal than the strips and possesses substantially greater inherent resiliency. This means as herein illustrated comprises a pair of wires 17 and 18 bent to substantially the same pattern and connected together in reversed relation by such

means as spaced metal ties or clips 19. It will be understood that a unit comprised of a pair of wires thus tied together is dimensioned to extend between adjoining rows of coil springs substantially from one end of the frame to the other, or from side to side as the case may be. It is contemplated that these wires may be bent on different patterns, but each pattern includes a plurality of bends, each providing a portion for connection with a helical spring which extends crosswise of the line of force exerted thereon by such spring. Inward bends are provided in the wire to receive the securing ties 19 without slippage. The terms "outward" and "inward" are herein used to express the direction of bend with respect to the longitudinal center line of an anchoring unit.

Referring to Figs. 1 and 5, each of the wires 17 or 18 has at regularly spaced intervals therein inward bends 20 and 21 preferably of generally V-shaped configuration. When the pair of wires is assembled in reversed relation, the apexes of these V-shaped bends are opposed and provide seats for the connecting ties 19. As will be noted in Fig. 1, the V-shaped bends 20 and 21 are so arranged that one bend, in this instance the bend 21, is located approximately at the center of the figure defined by four coil springs, while the other V-shaped bend 20 is located between an adjoining pair of coil springs in one of the rows. The helical spring receiving portions of the wires are designated 22 (Fig. 5) and are formed at the ends of the V-shaped bends 21 by reversely bending the wire upon itself, as at 23. The reverse bend 23 ends in a second reverse bend 24 from which the wire slopes outwardly substantially to the point where the next V-shaped bend 20 begins. It will be noted that the reverse bends 23 and 24 together form an S-shaped curve in the wire which increases its lateral resiliency.

While only one section of one wire has been described, it will be understood that the pattern of the bend is repeated throughout the lengths of both wires of the anchoring unit.

In the arrangement shown in Fig. 6, the wires of the anchoring unit are bent to a somewhat different pattern. In this form, the pair of wires 25 and 26 extend for the most part in substantially parallel relation. In the portions thereof which will be located near the center of the figure defined by four coil springs, the wires 25 and 26 are inwardly bent, as at 27, at two rather closely spaced points. These inward bends provide seats for connector ties 28. Between these points 27, the wires have an arcuate form, as at 29, which is outwardly convex providing portions 30 adjacent to the ties 28 for receiving the ends of the helical springs 16.

In the form shown in Fig. 4, the pattern of the bends is somewhat like that of the wires in the anchoring device of Fig. 6 in so far as it includes spaced parallel wires 31 and 32 having closely spaced inward bends 33 for connecting ties 34. The wire between the inward bends 33, however, has a deeper inward bend, as at 35, which increases the resiliency of the anchoring unit at this point and sharply defines the helical spring receiving portions 36.

The bed spring illustrated in Fig. 3 has a somewhat different arrangement of elements therein from that shown in Fig. 1. In this arrangement the frame 10, the coil springs 11 and the border wire 14 are as previously described, except that the coil springs of one row are stag-

gered with respect to the coil springs of the adjoining rows so that the springs are closer together along lines extending diagonally of the frame. In this arrangement, the coil springs in alternate rows are supported by wooden cross rails 12 and those of the intermediate rows are supported by diagonally extending cross wires 37 arranged to intersect below the coil springs of the intermediate rows. Such coil springs are suitably connected to the cross wires at the point of intersection.

As in the previously described form, the helical springs 16 are arranged to extend diagonally of the figure formed by four adjoining coil springs. The anchoring unit in this instance is shown as having the same form as the form of Fig. 1, but the units are arranged on lines diagonally of the frame and extend in both diagonal directions. The pattern of the bends of these anchoring units is so dimensioned that the outward bends 23 on the intersecting units coincide to the extent that the crosswise extending portions 22 thereof are disposed jointly to receive the end of a helical spring. The connecting ties 19 at the inward V-shaped bends 21 intersect. In this arrangement, the helical springs are doubly anchored to two interconnected anchoring units and the resiliency of both units acts in conjunction with each of the helical springs.

In each of the patterns of anchoring units heretofore described, the ends of the units may if desired be connected directly with the border wire by small helical springs 38 as shown in Fig. 3. Alternatively, however, the ends of the anchor units may terminate inwardly of the border wire by simply severing the wires outwardly beyond one of the connecting clips as shown in Figs. 4 and 6, or by cutting the wires approximately at the return bends 24 in the forms shown in Fig. 1. In these instances, the cut ends of the wires would be bent to provide an amply secure connection with the adjacent tie or ends of the helical springs.

From the foregoing it will be evident that a bed spring construction has been provided which embodies simple and effective means for securing the springs of the system in proper relation to each other. In each form, the wire portions perpendicular to the lines of force of the helical springs and the securing clips are close together so that the anchoring device has ample strength where needed to resist the pull of the helical springs. Otherwise, the flexibility and resiliency of the wires are not impaired. The anchoring means through its resiliency increases the effectiveness of the spring system. The efficient arrangement of a pair of wires bent to the same pattern makes possible the production of these units at a relatively low cost and the use of relatively small gauge wire instead of a metal strip effects a substantial saving of metal.

I claim as my invention:

1. A bed spring structure having, in combination, a series of coil springs, a plurality of helical springs for exerting their forces crosswise of certain coil springs, anchoring means for said helical springs including a pair of elongated members arranged to extend between rows of said coil springs for direct separable connection with said helical springs, and means at longitudinally spaced points in fixed position on said members for connecting said members together against separation, said members having bent portions thereon for connection with said helical springs

which extend substantially crosswise to the lines of force exerted by said helical springs.

2. For use in a bed spring structure having a series of coil springs and a plurality of helical springs for exerting their forces crosswise of certain coil springs, anchoring means for said helical springs including a pair of elongated members adapted to be arranged to extend between rows of said coil springs for direct connection with said helical springs, said members having bent portions thereon for connection with said helical springs extending substantially crosswise to the lines of force adapted to be exerted by said helical springs, and means located adjacent to the helical spring receiving portions of said members for connecting said members against lateral separation.

3. In a bed spring, an anchoring device for the crosswise extending helical springs thereof having, in combination, a pair of wires bent to the same pattern and arranged reversely and in spaced relation to each other, each of said wires having longitudinally spaced bends providing portions for engagement with said helical springs extending crosswise of the lines of force exerted by said helical springs, each of said wires having longitudinally spaced oppositely directed bends, and means seated in the last mentioned bends connecting said pair of wires.

4. An anchoring device for the crosswise extending helical springs of a bed spring having, in combination, a pair of spaced wires, each of said wires having longitudinally spaced V-shaped bends directed inwardly with respect to the other wire, and means engaging the apexes of said V-shaped bends for connecting said pair of wires in spaced relation, each of said wires having outwardly directed bends at the ends of certain of said V-shaped bends for engagement by said helical springs.

5. An anchoring device for the crosswise extending helical springs of a bed spring having, in combination, a pair of wires, each of said wires having longitudinally spaced V-shaped bends directed in assembly toward the other wire, and means seated in said V-shaped bends for connecting said wires in spaced relation, each of said wires having oppositely directed longitudinally spaced bends at the ends of certain of said V-shaped bends for engagement by said helical springs, said last mentioned bends being so dimensioned and arranged that when a plurality of said devices are arranged in overlapping end relation in the bed spring the helical spring engaged portions thereof register for joint engagement by said helical springs.

6. An anchoring device for the crosswise extending helical springs of a bed spring having, in combination, a pair of spaced wires each having pairs of closely spaced bends extending in assembly toward the other wire, and tie means seated

in said bends for connecting said pair of wires in spaced relation, each of said wires between the pairs of bends having an outwardly convex form providing points of attachment for said helical springs.

5 7. An anchoring device for the crosswise extending helical springs of a bed spring having, in combination, a pair of spaced wires, each of said wires having pairs of closely spaced bends extending in assembly toward the other wire, and tie means seated in said bends for connecting said pair of wires in spaced relation, each of said wires between the pairs of bends having deeper bends extending in the same direction as said pairs of bends, said pairs of bends and said deeper bends providing therebetween points of attachment for said helical springs.

10 8. An anchoring device for the crosswise extending helical springs of a bed spring having, in combination, a pair of spaced wires each having longitudinally spaced bends therein arranged in assembly to extend toward the other wire, tie means engaging said bends for connecting said pair of wires in spaced relation, and other bends in said wires arranged in assembly to extend outwardly and increasing the resiliency thereof and providing points for the separable connection of said helical springs thereto, certain of said tie means being located adjacent said last mentioned bends.

15 9. In a bed spring system having crosswise extending helical springs, intersecting anchoring means for said springs arranged to extend transversely of the spring system along intersecting lines comprising, in combination, elongated wires connected in spaced pairs, each pair of wires having bends therein providing points for connection with said helical springs, said bends being so dimensioned and spaced as to coincide at intersections of said anchoring means.
